DESIGN FOR A PORTABLE LIQUOR BAR

Ben C. Hershfield, New York, N. Y., assignor to J. P. Muller & Company, New York, N. Y., a corporation of New York

Application November 19, 1935, Serial No. 59,652

Term of patent 3½ years

To all whom it may concern:

Be it known that I, Ben C. Hershfield, a citizen of the United States and resident of New York, in the county of New York and State of New York,
have invented a new, original, and ornamental Design for a Portable Liquor Bar, of which the following is a specification, reference being had to the accompanying drawing, forming part thereof.

In the drawing:

Fig. 1 is a perspective view of a portable liquor

bar embodying the invention, the opposite end thereof being identical with the one shown.

Fig. 2 is a top plan view thereof in closed condition.

Fig. 3 is a top plan view of the same in open position.

I claim:

The ornamental design for a portable liquor bar, substantially as shown and described.

BEN C. HERSHFIELD.
